UNITED STATES PATENT OFFICE.

JOHN S. ALEXANDER, OF NEW YORK, N. Y.

RAILWAY AND OTHER TICKET.

No. 875,765.

Specification of Letters Patent.

Patented Jan. 7, 1908.

Application filed September 4, 1903. Serial No. 171,942.

To all whom it may concern:

Be it known that I, JOHN S. ALEXANDER, a citizen of the United States, and a resident of New York city, New York, have invented 5 certain Improvements in Railway and other Tickets, of which the following is a specification.

The object of my invention is to provide a simple, convenient and safe universal ticket, 10 which may be used over any transportation line irrespective of the rate of mileage fare charged thereby, the ticket having ample means for preventing it from being used successfully by any one other than the person to 15 whom it is issued, and being otherwise designed so as to overcome the objections, heretofore existing, to the mileage tickets issued by individual railroads or transportation systems and good only on such roads or 20 systems.

In the accompanying drawings:—Figure 1, is a view of a railroad ticket in accordance with my invention; Fig. 2, is a view of a book of validating stamps intended to be 25 used in connection with such ticket. Fig. 3, is a view of a ticket intended to be used upon a number of connecting lines, upon each of which a special ticket is needed; Fig. 4, is a rear view of the ticket shown in Fig. 3; and 30 Fig. 5, is a view illustrating a modification of my invention.

The ticket forming the subject of my invention, being intended for general use, has a blank space for the reception of the name 35 of the road or other transportation line on which the ticket is to be used, also spaces for receiving the names of the stations, ports, or other trip terminals between which the ticket is to be used, a space for indicating the distance 40 between the terminal points of the trip, a space for receiving the signature or other identifying mark, and, if desired, also, the address of the user of the ticket, a space for a registry number or other mark, and a 45 space for receiving certain validating stamps representing the distance covered by the trip for which the ticket is to be used, these stamps being also provided with spaces for receiving a signature or other identifying 50 mark peculiar to the user of the ticket. The distance may be expressed in any standard unit of measurement, or it may be expressed by an arbitrary term, for instance “zone”,

which may be of varying length according to circumstances.

The validating stamps are of different denominations, as indicated by the matter thereon, which may be engraved, written, stamped, embossed, punctured, or otherwise produced, or may be a composite of these 60 different methods of production, the stamps being preferably provided with adhesive material on the back so that they can be readily affixed to the ticket in the space provided for the purpose.

The validating stamps may be issued by any railway, traffic association or special company under agreement with the transportation lines accepting them for redemption on presentation, and the stamps may be 65 conveniently sold in books, such as shown in Fig. 2, each book containing any convenient number of stamps of different denominations which, for purpose of ready distinction one from another, may be differently colored 70 or otherwise provided with some permanent distinguishing mark.

For convenience, and to lessen the number of stamps which would be otherwise required, the use of a zone system is preferable, each zone representing a predetermined distance, say, for instance, two-and-a-half miles, and each group of stamps forming a single series or leaf of the book has a space for the reception of the signature or other 85 identifying mark of the purchaser, this space extending from end to end of the group, as shown in Fig. 2, so that some portion of the identifying mark will appear upon each stamp of the group, or each stamp of the 90 group, if desired, may bear a complete signature or other identifying mark, as shown for instance in Fig. 5.

The stamps of each group may be numbered or lettered consecutively or have other 95 marks indicating proper sequence, and in presenting the ticket to the conductor or other ticket collector the passenger may also be required to present his stamp book in order that the numbers or other sequence 100 marks upon the stamps remaining in the book can be compared with the numbers or other sequence marks upon the stamps affixed to the ticket, and in order, further, that comparison of the signature or other 105 identifying mark on the ticket may be made

with that upon the stamps, additional security against impersonation being also provided, if desired, by requiring the passenger to sign his name upon the blank reverse side 5 of the ticket as a means of identification.

In the drawing each group of stamps shown is lettered consecutively.

A ticket such as that constituting my invention is good on any railway or other 10 transportation line covered by the association or other organization issuing the ticket, irrespective of the mileage rate charged by the particular road or company upon which the ticket is being used. For instance, if the 15 validating stamps were charged for at the rate of five cents per zone and the mileage rate upon the road, or other transportation route upon which the ticket was being used, was two cents a mile, each zone stamp would 20 represent two-and-a-half miles of travel, while, if the mileage rate was two-and-a-half cents per mile, each zone stamp would represent two miles of travel and so on.

Each traveler can make up his own ticket 25 before going to the station, thereby saving the time usually expended in buying the ticket and lessening the number of ticket sellers necessary at large stations, and, as the 30 passenger's destination is designated by the ticket, the gate man has the same supervision as he would have of a special single ticket, thus overcoming an objection to ordinary mileage books and preventing admission of a passenger to a station platform 35 other than that at which his proper train is located. This renders unnecessary the plan which has sometimes been adopted of exchanging mileage strips for a special ticket at the ticket office, and as the ticket is absolutely 40 non-transferable, because valueless save in the hands of the proper holder, all rebates or deposits to be returned in case there is no improper use of mileage strips are rendered unnecessary.

45 The validating stamps and skeleton tickets may be sold either by the companies belonging to the association or by an organization at union agencies, and settlement may be made daily through a clearing house, thus dispensing with the heavy correspondence 50 and clerical labor necessary to effect settlements with individual companies, for it is well known that under the present practice a conductor or other ticket taker often collects 55 on a single trip, or even in a single car, coupons from a dozen or more different issues of tickets, each requiring separate treatment in the auditor's office.

Each road adopting the improved ticket 60 can furnish a table of distances in zones, either embodied in the usual folder or in separate form, and in compiling this table each road can arbitrarily fix the rate of its own zone, the distance in each case being that 65 for which a passenger is carried for the

amount paid for each zone stamp, and special portions or sections of a line, for which a special rate is charged, may have an arbitrary zone value not determined by the length of said section, for instance, a bridge, 70 a ferry, a section of road for which a heavy trackage fee or rental is paid, or any section of line run under special conditions, may have a zone value much greater than other portions of the line. Thus if each zone 75 stamp represents a distance of two miles, a bridge or ferry only one mile in extent might have an arbitrary value of five zones, or the distance between two stations ten miles apart served by competing lines might 80 count as one zone, while beyond said stations in either direction a zone would represent only two miles.

Once put in force a zone table needs no attention until, for some reason, a new one is 85 compiled, although the zone tables may be revised as often as the timetables, to suit the wishes of the management and without conflicting with the system or requiring any change in the stamps or skeleton tickets. 90 Special zone tables may be compiled for express trains, giving only express stations, so that it may appear in condensed form on express train time tables. The stamps can also be used for paying Pullman car fare, 95 trolley car fare, steam-boat passage, stage fare, or, in fact, can be adapted to any means of transportation within the regulations of the company, association or other organization issuing the stamps. 100

All zone stamps can be redeemed at face value, less a commission for service, by the company or association issuing the stamps on presentation by the transportation lines accepting tickets validated by such stamps, 105 and if the stamps are issued by a special company organized for the purpose those collected each day can be sent for redemption in the same manner as bank drafts or checks, settlement becoming thus a simple 110 matter of banking instead of ticket auditing.

Excess baggage can be paid for by issuing a ticket for the required amount and affixing thereto zone stamps representing a sum equal to the charge for such excess baggage, 115 thus obviating the necessity for the special excess baggage books issued by some lines.

The skeleton tickets are preferably provided with stubs, as shown in Fig. 1, and perforated so that the ticket can be readily detached from the stub, thereby providing for keeping a stub record of each ticket used. 120

That there is a demand for a system which will satisfactorily cover the points above noted is shown by the many expedients that 125 have been adopted in the effort to solve the problem. Nearly every method now employed, however, fails to meet the demands of the situation in one or more respects, for instance, the plan most generally used and 130

known as the thousand mile rebate ticket, which compels the purchaser to deposit a certain amount above the cost of the ticket as a guarantee of good faith in making the purchase, such amount to be returned when the mileage strips have all been used, is an onerous tax upon the purchaser and the rebates are often disputed, causing more or less controversy. The plan which requires the holder to exchange his mileage strips for an ordinary ticket before boarding the train destroys one of the greatest advantages of the general idea involved in a mileage ticket, that is to say, the ability to immediately get aboard the train without the necessity of stopping to purchase a ticket or without regard to the local ticket agent.

As the passenger's destination must be indicated upon the ticket before he passes the gate-man the passenger cannot board an express train making few stops and then tender mileage strips for a station a short distance from the starting point with the excuse that he was not advised that the train did not stop at such station, thus overcoming a serious abuse to which ordinary mileage books are subjected. Furthermore, my improved ticket, with its validating stamps, does not provide the same opportunity as an ordinary mileage book for dishonesty on the part of the conductor, who may turn in parts of mileage strips for cash fares.

For use in making trips over routes covered by a number of connecting lines each requiring its own ticket I provide a multiple ticket such as shown in Figs. 3 and 4, said ticket having as many subdivisions as desired each with detachable coupon, to which the validating stamps are attached, thus the ticket shown in Fig. 3 has had three of its subdivisions filled up for a trip between terminals requiring the use of three different lines, the first covering two zones, the second covering one zone and the third covering two zones, the removal of the coupon carrying the validating stamps from the first subdivision of the ticket showing that that stage of the

journey has been paid for while the others have not. The signature or other identifying mark is applied to the back of this ticket as shown in Fig. 4. By the use of a multiple ticket of this character, independent or separate tickets for each stage of a journey are rendered unnecessary, and a given number of ticket forms will cover a correspondingly increased period of use. The same form of ticket can also be used with advantage for trips back and forth between stations on the same line, one subdivision being sufficient for each trip.

While I have shown and described my invention as embodying the use of adhesive stamps to be applied to a ticket, certain features of my invention are also applicable to coupons intended to be torn from a book or other group or collection of the same, and in this connection I regard the coupon as the equivalent of the stamp, and intend it to be included within the scope of my claims.

Having thus described my invention, I claim and desire to secure by Letters Patent:

1. A passage ticket having sub-divisions, each having marked upon it the distance for which it is intended to serve as fare, each subdivision having a coupon bearing a stamp or stamps marked for a like distance.

2. A passage ticket having sub-divisions, each having marked upon it the distance for which it is intended to serve as fare, each sub-division having a coupon bearing a stamp or stamps marked for a like distance, said ticket having an identifying mark peculiar to the user of the same, and the stamp or stamps upon each sub-division of the ticket also bearing an identifying mark.

In testimony whereof, I have signed my name to this specification, in the presence of two subscribing witnesses.

JOHN S. ALEXANDER.
